CAN DUMPING MACHINE

Robert J. Newton, Honolulu, Territory of Hawaii,
assignor to California Packing Corporation, San
Francisco, Calif., a corporation of New York

Application September 14, 1945, Serial No. 616,176

10 Claims. (Cl. 214—1.1)

1

My invention relates to can dumping machines, more particularly to machines designed to receive a stack of trays, each carrying a layer of cans, pick up the trays, one layer at a time, and invert them so that the cans may be fed into a labeling machine or other apparatus, and the trays removed or reuse.

Among the objects of my invention are:

First, to provide a can dumping machine which is particularly designed for use in conjunction with an automatic tray removing apparatus disclosed in the copending application of Robert Berthe et al., Serial No. 616,780, filed September 17, 1945.

Second, to provide a machine of this character wherein the cans are not violently handled or in any way subjected to damage.

Third, to provide a machine of this character, which automatically adjusts itself to the stack of trays and cans as the stack is depleted.

Fourth, to provide a machine of this character, which incorporates a novel tray engaging and releasing means capable of manual operation to engage the tray, and automatic operation to release the tray.

With the above and other objects in view, as may appear hereinafter, reference is directed to the accompanying drawings, in which:

Fig. 1 is a side elevational view of the can dumping machine with the elevator moving toward its tray receiving position.

Fig. 2 is a fragmentary plan view of the elevator showing the limit switch unit.

Fig. 3 is a fragmentary side elevational view of the dumping machine with the elevator in its dumping or discharging position.

Fig. 4 is a fragmentary sectional view of the dumping machine taken through 4—4 of Fig. 1.

Fig. 5 is a fragmentary view similar to Fig. 4, but showing the elevator in its tray engaging position.

Fig. 6 is a fragmentary sectional view through 6—6 of Fig. 1, showing by solid lines the latching mechanism in its latching position, and by dotted lines in its released position.

Fig. 7 is a similar fragmentary sectional view of the latching mechanism when the elevator is in its dumping position, the view being taken through 7—7 of Fig. 3.

Fig. 8 is a fragmentary sectional view through 8—8 of Fig. 3, showing the elevator centering means.

My dumping machine includes a pair of A-frames 1, the upper ends of which journal a cross shaft 2. Secured to the cross shaft inwardly from each A-frame is a relatively large dumping sprocket 3. An elevator chain 4 passes over each sprocket. The lower end of one chain passes around an idler pinion sprocket 6 carried by one of the A-frames near its lower end, whereas the

2

other elevator chain is engaged by a corresponding drive pinion sprocket 6 supported from the other A-frame.

The pinion sprockets 6 are preferably so located that the chains extend vertically between the forward sides of the dumping sprockets and pinion sprockets.

The drive pinion sprocket is connected by a suitable drive means 7 to a reversible electric motor 8 which may be equipped with a suitable brake 9.

The elevator chains 4 are adapted to support an elevator structure 11. The elevator structure includes a plate 12 and a pair of side walls 13.

Brackets 14 are secured to the outer sides of the side walls 13, preferably two pair of brackets being provided on each side wall. The brackets extend vertically, and the upper extremities of the brackets associated with each side wall, journal a common rocker shaft 15. Adjacent each bracket the rocker shaft is provided with levers 16 which extend to the normally lower or extended margin of the side walls 13. The extremities of the levers 16 carry latch bars 17 which move in guideways 18. The guideways and the latch bars 17 are located in a common plane parallel to the plate 12 of the elevator. As will be described in more detail hereinafter, the latch bars 17 are adapted to engage trays A, each of which carries a layer of cans B, the trays being so suspended by the latch bars that the cans are located between the trays and the plate 12.

One lever 16 of each set corresponding to the side walls 13, is provided with an upwardly extending arm 19. These arms are connected by a suitable link and lever means 20 extending across the normally upper side of the plate 12, so that the two sets of latch bars are moved relatively inwardly or outwardly in unison.

One of the rocker shafts 15 is provided with a handle arm 21 located so that it can be conveniently grasped when the elevator is lowered onto a stack of trays and cans. Adjacent one side wall the elevator 11 is provided with a normally upwardly extending cam bracket 22 which pivotally supports a cam segment 23 connected by a link 24. The link 24 is connected to an arm 25 extending upwardly from one of the levers 16. The operation of the cam segment will be described in more detail hereinafter.

The elevator 11 is provided near each corner and at the central portion of each side member 13 with a downwardly directed and outwardly curved guide finger 26 so as to guide and direct the elevator 11 downwardly over a stack of trays and cans.

The elevator 11 is attached to the elevator chains 4 by suspension brackets 27 normally extending upwardly from the center of each side of the elevator. Each suspension bracket has

two spaced points of connection with its elevator chain, so that the elevator 11 may be raised and then rotated as the points of support of the suspension brackets trace the curvature of the dumping sprockets 3.

Rearwardly of the A frames 1 is a frame structure 28 which supports a downwardly and rearwardly directed chute 29. The frame structure and chute are so arranged that when the elevator 11 has been raised and overturned by movement around the dumping sprockets 3, its plate 12 slopes downwardly and rearwardly in approximate alignment with the chute 29. In order to direct the elevator into proper alignment with the chute 29, guide posts 30 are provided on each side. These may co-act with a pair of the guide fingers 26, as shown best in Fig. 8.

Suitably located on the frame structure 28 is a trip element 31 which engages the cam segment 23 to move the latch bars 17 from their inner tray-supporting to their outer tray-releasing positions.

The plate 12 of the elevator supports a switch control arm 32 which extends downwardly through a clearance slot 33 to engage the uppermost layer of cans contained in the stack of cans and trays. The switch control arm 32 is rigidly joined to a lever arm 34 located in the normally upper or outer side of the plate 12. The lever arm 34 is yieldably engaged by a spring 35 so that the switch control arm 32 is in effect held by the spring in a downwardly inclined position. The lever arm 34 is positioned so that it will actuate a switch 36 mounted on the plate 12.

Operation of my can dumping machine is as follows: The trays A and cans B are wheeled into position between the A-frames 1 on a carriage or truck C. The carriage is preferably arranged to support a pair of trays side by side. Each tray carries a layer of cans B, and the trays are arranged in stacks, each tray resting on the layer of cans below. The trays are provided with cross cleats D so that the cleats in resting on the cans below, provide spaces into which the latch bars 17 may enter. The side walls 13 of the elevator are of such height that when the plate 12 rests on the uppermost layer of cans, the latch bars 17 are in position to enter between the cleats of the trays supporting the upper layer of cans, all as shown best in Fig. 5.

The elevator 11 is moved downwardly until the plate 12 rests on the uppermost layer of cans. The movement of the elevator 11 may be stopped automatically by operation of the control arm 32 on the switch 36, or if desired, a manually operated push button may be employed to stop downward movement of the elevator. When the elevator 11 is in the position shown in Figs. 5 and 6, the latch bars 17 are moved from the position shown in Fig. 4 to the position shown by solid line in Fig. 4, and by dotted line in Fig. 6 to the solid line positions shown in Figs. 5 and 6.

The elevator 11 is then raised by action of the motor 8, inverted or tilted into substantial alignment with the chute 29. This is the position shown in Fig. 3. When the elevator reaches this position the motor 8 is stopped by a suitable manually operated push button, or by an automatic switch, not shown. Automatically, as the elevator reaches the position shown in Fig. 3, the cam segment 23 engages the trip 31 moving the latch bars 17 to their laterally outer positions, thereby releasing the trays. The layer of cans

thereupon slide from the elevator 11 onto the chute 29, and the trays ride on the cans.

It is contemplated that the cans with the trays riding thereon, will move into the tray-removing apparatus described in the aforementioned co-pending application of Robert Berthe et al., although of course, other apparatus may receive the cans and trays.

After the layer of cans and the trays which formerly supported it have moved from the elevator 11, the motor 8 is reversed, causing the elevator to return to its initial position and move downwardly until it rests again on the remaining stack of trays and cans. The cycle of operation is then repeated.

Many other embodiments of the invention may be resorted to without departing from the spirit of the invention.

I claim:

20 1. A can dumping machine, comprising: an elevator unit including suspension and latch means at its sides for engaging and suspending a tray under said elevator unit, whereby a layer of cans supported on said tray are restrained between the tray and elevator unit; means including a vertical lift and wheels around which said lift extends for raising, inverting and inclining said elevator unit whereby said tray terminates in a position above said layer of cans; and means for releasing said tray engaging latch means when said elevator is inverted and inclined whereby said layer of cans and tray slide from said elevator.

25 2. A can dumping machine, comprising: a frame structure; dumping wheels journaled at the upper part of said frame structure; flexible means rising substantially vertically and passing over said dumping wheels; an elevator suspended between and carried by said flexible means, said 30 elevator adapted to be raised, and inverted to inclined position by movement about the axis of said dumping wheels; means under said elevator for engaging and carrying a tray loaded with a layer of cans for inversion with said elevator 35 thereby to dispose the layer of cans below said tray; and means for releasing said tray and cans for discharge from said elevator when said elevator is inverted and inclined.

35 3. In a handling apparatus for lifting and inverting trays, each carrying a layer of cans and initially disposed in a stack, the combination of: an elevator having a surface adapted initially to overlie a layer of cans, and means carried by said elevator for engaging and suspending the 40 tray supporting said layer of cans; means for raising, inverting and tilting said elevator whereby said surface forms an inclined chute for the 45 discharge of said cans; and means for releasing said tray from said elevator upon inversion of said elevator whereby said tray is discharged with, but above said cans.

40 4. In a handling apparatus for lifting and inverting trays, each carrying a layer of cans and initially disposed in a stack, the combination of: an elevator having a surface adapted initially to overlie a layer of cans on the uppermost tray of said stack, latch elements carried by said elevator and movable laterally to engage and suspend said tray; handle means accessible when said elevator 45 is in proximity to said stack for moving said latch elements into engagement with said tray; and a cam element for releasing said latch elements from said tray; means for raising, inverting and inclining said elevator; means engageable with said cam element when said elevator is

inverted and inclined for releasing said tray, whereby said layer and can may slide from said elevator with said tray uppermost.

5. In a handling apparatus for lifting and inverting trays, each carrying a layer of cans and initially disposed in a stack, the combination of: an elevator having a surface adapted initially to overlie a layer of cans on the uppermost tray of said stack; latch elements carried by said elevator and movable laterally to engage and suspend said tray; handle means accessible when said elevator is in proximity to said stack for moving said latch elements into engagement with said tray; and a cam element for releasing said latch elements from said tray; a pair of inverting wheels; flexible means rising substantially vertically and passing over said wheels; a reversible drive for said flexible means; said elevator being suspended between said flexible means and adapted to be raised and pivoted about the axis of said inverter wheels to an inverted inclined position whereby said layer of cans rests on said surface and said tray is located above said cans; means engageable with said cam element for withdrawing said latch elements from said tray whereby said tray and cans may slide from the elevator.

6. In a handling apparatus for lifting and inverting trays, each carrying a layer of cans and initially disposed in a stack, the combination of: an elevator having a flat surface adapted to overlie a layer of cans supported on the uppermost tray of a stack of trays and cans, side members bordering said surface adapted to fit over the sides of said layer of cans and the tray thereunder, and a plurality of latch elements carried by said elevator and linked together for movement in unison into and out of engagement with said uppermost tray; means for raising, inverting and inclining said elevator from a position on said stack and returning said elevator to said stack; means for actuating said latch elements to engage the uppermost tray when said elevator is on said stack, and means for actuating said latch elements to release said tray when said elevator is inverted and tilted, whereby said layer of cans and tray may slide from said elevator.

7. In a handling apparatus for lifting and inverting trays, each carrying a layer of cans and initially disposed in a stack, the combination of: an elevator having a flat surface adapted to overlie a layer of cans supported on the uppermost tray of a stack of trays and cans, side members bordering said surface adapted to fit over the sides of said layer of cans and the tray thereunder, and a plurality of latch elements carried by said elevator and linked together for movement in unison into and out of engagement with said uppermost tray; a pair of inverting wheels; flexible means rising substantially vertically and passing over said wheels; a reversible drive for said flexible means; means for actuating said latch elements to engage the uppermost tray when said elevator is on said stack; and means for actuating said latch elements to release said tray when said elevator is inverted and tilted, whereby said layer of cans and tray may slide from said elevator.

8. In a handling apparatus for lifting and inverting trays, each carrying a layer of cans and initially disposed in a stack, the combination of: an elevator having a surface adapted initially to overlie a layer of cans on the uppermost tray of said stack; latch elements carried by said elevator and movable laterally to engage and suspend

said tray; handle means accessible when said elevator is in proximity to said stack for moving said latch elements into engagement with said tray; and a cam element for releasing said latch elements from said tray; a pair of inverting wheels; flexible means rising substantially vertically and passing over said wheels; a reversible drive for said flexible means; said elevator being suspended between said flexible means and adapted to be raised and pivoted about the axis of said inverter wheels to an inverted inclined position whereby said layer of cans rests on said surface and said tray is located above said cans; means engageable with said cam element for withdrawing said latch elements from said tray whereby said tray and cans may slide from the elevator; and means for stopping said reversible drive as said elevator moves into contact with the stack of cans and trays.

9. In a handling apparatus for lifting and inverting trays each carrying a layer of cans and initially disposed in a stack the combination of: an elevator having a flat surface adapted to overlie a layer of cans supported on the uppermost tray of a stack of trays and cans, side members bordering said surface adapted to fit over the sides of said layer of cans and the tray thereunder, and a plurality of latch elements carried by said elevator and linked together for movement in unison into and out of engagement with said uppermost tray; means for raising, inverting and inclining said elevator from a position on said stack and returning said elevator to said stack; means for actuating said latch elements to engage the uppermost tray when said elevator is on said stack, means for actuating said latch elements to release said tray when said elevator is inverted and tilted, whereby said layer of cans and tray may slide from said elevator; and means for stopping said reversible drive as said elevator moves into contact with the stack of cans and trays.

10. In a handling apparatus for lifting and inverting trays, each carrying a layer of cans and initially disposed in a stack, the combination of: an elevator having a flat surface adapted to overlie a layer of cans supported on the uppermost tray of a stack of trays and cans, side members bordering said surface adapted to fit over the sides of said layer of cans and the tray thereunder and a plurality of latch elements carried by said elevator and linked together for movement in unison into and out of engagement with said uppermost tray; a pair of inverting wheels; flexible means rising substantially vertically and passing over said wheels; a reversible drive for said flexible means; means for actuating said latch elements to engage the uppermost tray when said elevator is on said stack; means for actuating said latch elements to release said tray when said elevator is inverted and tilted whereby said layer of cans and tray may slide from said elevator; and means for stopping said reversible drive as said elevator moves into contact with the stack of cans and trays.
